US0D1064471S

(12) **United States Design Patent** (10) Patent No.: **US D1,064,471 S**
 Yosef et al. (45) Date of Patent: ** Feb. 25, 2025

(54) **DETACHABLE FLUID DISTRIBUTOR FOR ROBOTIC SWIMMING POOL CLEANER**

(71) Applicant: **Maytronics Ltd.**, Kibbutz Yizrael (IL)

(72) Inventors: **Binyamin Yosef**, Moshav Prazon (IL);
Tom Chovers, Moshav HaYogev (IL)

(73) Assignee: **Maytronics Ltd.**, Kibbutz Yizrael (IL)

(**) Term: **15 Years**

(21) Appl. No.: **35/519,745**

(22) Filed: **Dec. 28, 2023**

(80) **Hague Agreement Data**

Int. Filing Date: **Dec. 28, 2023**

Int. Reg. No.: **DM/234440**

Int. Reg. Date: **Dec. 28, 2023**

Int. Reg. Pub. Date: **Jan. 19, 2024**

Primary Examiner — Patricia A Palasik

(57) **CLAIM**

The ornamental design for a detachable fluid distributor for robotic swimming pool cleaner as shown and described.

DESCRIPTION

1. Detachable fluid distributor for robotic swimming pool cleaner

1.1 : Perspective

1.2 : Back

1.3 : Top

1.4 : Front

1.5 : Left

1.6 : Right

1.7 : Bottom

The characteristic features of the design lie in the shape and pattern of the detachable fluid distributor for robotic swimming pool cleaner as shown.

1 Claim, 7 Drawing Sheets
